UNITED STATES PATENT OFFICE.

JOHN EMANUEL JOHNSON AND CHARLES H. OSLUND, OF WORCESTER, MASSACHUSETTS,
ASSIGNORS TO THE O. AND J. MACHINE COMPANY, OF WORCESTER, MASSACHUSETTS,
A CORPORATION OF MASSACHUSETTS.

LABEL-ADVANCING MECHANISM.

1,300,407.

Specification of Letters Patent. Patented Apr. 15, 1919.

Application filed August 2, 1916. Serial No. 112,706.

To all whom it may concern:

Be it known that we, JOHN EMANUEL JOHNSON and CHARLES H. OSLUND, said JOHNSON being a subject of the King of Sweden and said OSLUND, a citizen of the United States, both residing at Worcester, in the county of Worcester and State of Massachusetts, have invented a new and useful Label-Advancing Mechanism, of which

10 the following is a specification.

This invention relates to a pasting mechanism, and while capable of general use, it may be considered as an improvement over the pasting machine set forth in our application for Letters Patent filed October 22, 1915, Serial No. 57,349, and is particularly adapted to be applied to the same class of machines.

The principal objects of this invention are to provide the label holding mechanism with improved means for applying pressure to the labels and improved means for releasing the same so as to permit of filling the label holder readily; to provide improvements in the means for moving the label holding device; and other improvements in the details of construction.

Reference is to be had to the accompanying drawings in which—

30 Figure 1 is a side elevation of a labeling device constructed in accordance with this invention;

Figs. 2 and 3 are end views of one of the weights for feeding the label holding plates showing the locking device in two different positions;

35 Figs. 4 and 5 are side elevations on enlarged scale of the weights for feeding the label holders down and holding them in position;

40 Fig. 6 is a plan of the end of the rack shown in Fig. 5, and

Fig. 7 is an end view of the label holder looking in the direction of the arrow 9 in

45 Fig. 1.

The machine is shown as comprising a frame 42 having a stand 153 extending upwardly therefrom on which the label-holder is mounted. On the top of this stand is a horizontally movable support 154 adapted to be held by a spring 155 in its forward operating position against an adjustable stop 56.

Means for operating this is not shown in

full as it can be operated as in the above mentioned case by means of a swinging arm 196 and operating lever or fork 191. The bottom of the support 154 is provided with two lugs 197 so that the arm 196 positively operates the support 154 in both directions. On the top of this support is a vertical stud 157 on which a bracket 158 is mounted. This bracket is provided with an adjusting screw 59 for changing the height thereof.

Projecting upwardly at an angle from the bracket 158 are a pair of parallel rods 160. Between these rods are a series of cross bars 161, four being shown. They are adjustably fixed in position on the rods 160 by means of set screws so as to be adjusted for labels of any desired width. Each of these cross bars has a plurality of guides 162 constituting one side of the label holder. They are also provided with arms 164 mounted adjustably. Each arm 164 supports one or more guides 169 which constitute the ends of the label holder. In this way as in our above identified case two label holders are provided, one for body labels and the other for neck labels. Each of the guides 162 and 169 has a hook 171 on the end facing inwardly to hold the labels. They permit the labels to be withdrawn from between them as in the above identified case.

The bracket 158 is provided with a rearward extension 172 on which is mounted a plate 174. This is connected with the rods 160 by tie rods 173. The plate 174 is provided with a pair of guide rods 175 for supporting rollers 177 which by means of weights 18 are held down on the rods 175. The weights are provided with sockets 19 having springs therein. Each of these springs bears against the end of a rod 179 which is guided in the socket and in a projection 20 on the weight. The springs normally press these rods down so that pins 21 thereon engage the ends of slots 22 in the projections 20. The rods 179 carry at their ends plates 180 adapted to engage the end 100 label in each label holder and hold the labels therein in proper position against the hooks 171. The weights 18 hold the rods 179 down toward the hopper so as to keep the labels in proper position.

105 One of the guide rods 175 is shown as smooth on top, but the other is provided with a rack 24 for receiving a pawl 25 car-

ried by the weight 18. This pawl is pivoted so as normally to engage the teeth of the rack and prevent the weight being slid backwardly along the rod. On the end of 5 the weight is a pivoted latch 26. This is provided with two projections 27 and 28. The end of the guide rod 175 is reduced to half width at the point 29 as shown in Fig. 6 and when the latch is in the position shown 10 in Fig. 3 its prong 27 is capable of sliding into this notch which constitutes a stop to prevent the weight and connected parts moving down the guide rod 175. This is the position the parts are brought to when it is 15 desired to withdraw the plates 180 for the purpose of filling the hoppers.

The normal position of this latch 26 is part way between the two positions shown 20 in Figs. 2 and 3 so that the prong 27 does not engage in the notch 29 and the prong 28 is also withdrawn from engagement with the pawl 25. In this position of the parts the pawl 25 engages its teeth and the plate 180 is fed down by gravity, the weight of the 25 member 18 serving to assist in moving it along. It is to be noted however, that the plate or plunger 180 is yieldingly connected with this weight.

After the plunger has fed forward sufficiently and it is desired to refill the hopper 30 the latch 26 is swung around farther to the right from the position shown in Fig. 2 so that the prong 28 engages under the pawl 25 and raises it away from its teeth. Then the 35 weight with its rod 179 and plate or plunger 180 can be slid along the rod up to the end and the latch then turned over into the position shown in Fig. 3 to permit of filling the hopper.

40 Mounted on the bracket 30 carried by the stand 153 are adjusting screws 31 on which rests the containing vessel or paste pot 223. These screws can be adjusted to regulate the angle at which the paste-pot is located as 45 will be obvious. For the purpose of securing the paste pot in its adjusted position it is provided with a downwardly extending hook lug 33 and a locking pin 34 is forced through a passage in the stand 153 so that 50 its beveled end comes over the lug 33 and holds the pot in position.

The top of the paste pot is protected by a cover 50 having an opening at the top surrounded by an upwardly projecting wall 51 55 slotted at its ends to receive the end of the paste roller 221. This cover is provided with a slanted plate 53 to receive the drippings from above and is held in position by two snap-springs 54 and 55. In this way it 60 will be seen that the machinery below is fully protected from the drippings of paste.

As in the other case the paste drum is operated from the shaft 106 through sprocket wheel 225 and chain 224. Furthermore although not constituting part of 65

this invention it will be understood that the pasting operation is carried out by the paste roller 221 on a movable member 220 engaging the pickers 200 and moving up and down from the pickers to the drum. These pickers are shown as mounted on a sliding sleeve 70 on a shaft 202 and operated by a link 211.

Although we have described the container 223 as a paste pot and referred to the ether mechanism as designed for the purpose of 75 pasting labels, we are aware of the fact that this part of the device either in the form shown or other forms can be used for coating purposes in general, and that it is not necessarily limited to pasting. We are 80 also aware of the fact that changes in the construction and design of the parts can be made without departing from the scope of the invention as expressed in the claims. Therefore we do not wish to be limited in 85 these respects, but what we do claim is:—

1. In a labeling machine, the combination with a label holding and label feeding device of an inclined fixed rod, a roller supported on said rod and mounted to roll 90 down the same, a weight supported by the roller below the rod, a movable rod yieldingly connected with said weight but movable therewith, and a plate on the movable rod for applying pressure to a pile of labels 95 below.

2. In a labeling machine, the combination with a label holding and label feeding device of an inclined fixed rod, a roller mounted to roll down the rod, a weight supported 100 from the roller, a latch pivoted on the weight for holding the weight only at the end of the rod when the latch is turned to a certain position, and means connected with the weight for applying the pressure thereof 105 to a pile of labels.

3. In a labeling machine, the combination of means for holding a pile of labels, a plate for engaging said labels and pushing them toward the point of discharge, a fixed rod, a 110 movable rod connected with the plate, a weight yieldingly and movably connected with the movable rod, said weight having a roller adapted to roll along the surface of the fixed rod, said fixed rod having a notch 115 at its end, and a pivoted latch on the weight having a projection adapted to engage in said notch only when the parts are moved to the end of the rod.

4. In a labeling machine, the combination 120 with a label holding and label feeding device of an inclined fixed rod having teeth on its upper surface, a roll adapted to move along said rod, a weight supported by the roll, a pawl connected with the weight and adapted to engage said teeth, means connected with the weight for applying pressure to a pile of labels, and a pivoted latch 125 having a projection for engaging the rod and holding the weight at the upper end 130

thereof when the latch is in one position and having means for engaging the pawl when the latch is moved to the opposite position and forcing the pawl out of engagement 5 with the teeth of the rack.

5. In a labeling machine, the combination with a label holding and label feeding device of an inclined rod, a roll adapted to move along said rod, a weight supported by 10 the roll on the opposite side of the rod, means connected with the weight for applying pressure to a pile of labels, and a pivoted latch having a projection for engaging the rod and holding the weight at the upper 15 end thereof when the latch is in one position and having means whereby when the latch is moved to the opposite position the weight can be moved toward said end.

6. In a labeling machine, the combination 20 with a label holding and label feeding device of an inclined fixed rod having teeth on its upper surface, a roll adapted to move along said rod, a weight supported by the roll below the rod, a pawl connected with

the weight and adapted to engage said 25 teeth, and means connected with the weight for applying pressure to a pile of labels.

7. In a labeling machine, the combination with a label holding and label feeding device with an inclined fixed rod having teeth 30 therealong, a roller adapted to roll down the rod, a pawl movable with the roller and adapted to engage the teeth to prevent the movement of the roller up the rod, and means connected with said roller for applying 35 pressure to a pile of labels below.

8. In a labeling machine, the combination of a label holder, a guide rod extending upwardly therefrom, means movable along the guide rod for applying pressure to the labels 40 in said label holder, and means carried by the last named means for normally preventing the pressure applying means from being raised along the rod.

In testimony whereof we have hereunto 45 affixed our signatures.

JOHN EMANUEL JOHNSON.
CHARLES H. OSLUND.
